UNITED STATES PATENT OFFICE

134,475

DESIGN FOR A PRACTICE TYPEWRITER

Amy Emanuel, Asheville, N. C.

Application September 30, 1942, Serial No. 108,367

Term of patent 7 years

To all whom it may concern:

Be it known that I, Amy Emanuel, citizen of the United States, residing in the city of Asheville, county of Buncombe, and State of North Carolina, have invented a new, original, and ornamental Design for a Practice Typewriter, of which the following is a specification, reference being had to the accompanying drawing, forming part thereof.

Fig. 1 is a perspective view of a practice typewriter showing my new design; and,

Fig. 2 is an end elevational view thereof.

I claim:

The ornamental design for a practice typewriter, substantially as shown.

AMY EMANUEL.
